Frederick Emil Rommel, West Dulwich, London, England, assignor to Telephone Manufacturing Company Limited, London, England.

Application August 23, 1954, Serial No. 451,374

Claims priority, application Great Britain August 24, 1953

8 Claims. (Cl. 200—104)

This invention relates to electromagnetic switches of the type employing a plurality of contact sets, a pre-selector or so-called finger magnet pertaining to each contact set, and a main operating magnet. The action is such that upon energisation of a finger magnet a member, which can be identified as an interference piece, is moved into a position such that when the main magnet is energised the contacts of the pertaining set are actuated; the sets of which the finger magnets have not been previously energised are not actuated. Switches of these types are used in cross-bar telephone systems; one such switch is described in United States Patent No. 2,630,500, issued March 3, 1953, in the name of Frederick E. Rommel. A switch of this type is also described in a co-pending United States application No. 451,375 filed August 23, 1954, now Patent No. 2,810,040. The present invention is concerned with an improved construction of switch.

In a switch of this type the design of the interference piece is a matter of difficulty. In the first place cross-bar telephone systems are very often used in remote rural areas, so that reliability over long periods is of importance even more than in telephone circuits in general. Secondly, as will be explained in more detail hereinafter, the interference piece must be made so as to be capable of substantially independent motions in two directions in response to the finger magnet and to the main magnet respectively, but at the same time any movement which would give rise to incorrect operation of the switch must be avoided.

It is convenient to refer to the two motions of the interference piece as being in respectively the interfering direction, in which it is moved by the finger magnet, and the actuating direction, in which it is moved by the main magnet to cause actuation of the related contact set. In accordance with the invention, there is provided an electromagnetic relay comprising a main operating magnet, a plurality of contact sets, an operator for the contacts of each of said contact sets, a plurality of finger magnets corresponding to said contact sets and each having an armature carrying an interference piece arranged on operation of the finger magnet to be moved in an interfering direction, so as to be interposed between an actuator, moved in an actuating direction by the armature of the main magnet, and the operator of the corresponding contact set and wherein guide surfaces are provided to limit the motion of each of the interference pieces in the actuating direction when they are moved in the interfering direction.

In accordance with a further feature of the invention the movement of the interference piece is limited also in a direction, other than the actuating direction, which is at a substantial angle to the interfering direction. In a preferred embodiment of the invention to be described hereinafter the interfering and actuating directions are approximately at right angles, and the interference piece

2

is limited in its movement in that direction which is at right angles to both of those directions.

Other features and advantages of the invention will appear from the following description of this preferred embodiment thereof, given by way of example, in conjunction with the accompanying drawings. The switch shown, and to be described, is of the cross-bar type referred to above.

In the drawings:

- 10 Figure 1 is a side elevation of the switch;
- Figure 2 is a plan view of the same switch;
- Figure 3 is an end elevation of the switch;
- Figure 4 is a fragmentary section on the line x—x of Figure 2;
- 15 Figure 5 is a side view, on an enlarged scale, of one of the finger magnet armatures, together with the attached interference piece;
- Figure 6 is an end view, on an enlarged scale, of the armature and interference piece of Figure 5;
- 20 Figure 7 is a side view of an interference piece before being deformed, and
- Figure 8 is a plan view of the guide block.

The switch shown in these drawings is built up on a base plate 10 of soft iron sheet; "soft" is to be understood as meaning material of high magnetic permeability and low retentivity, such as is suitable for use with electromagnetic devices.

At its one end this baseplate has an upwardly turned flange 10a which supports three finger magnets 11; these magnets have cores 12 which are screwed into and through flange 10a and there held by locknuts 13. As will be seen, these magnets lie with their cores parallel to each other and to the baseplate. At the other end of the baseplate is another flange 10b and three further finger magnets 14 have their cores 15 screwed into the flange, and held by locknuts 16. The upper edge of flange 10b is again turned over, at 10c. The cores of finger magnets 14 are also parallel to each other and to baseplate 10, and the six finger magnets all lie compactly in one layer on the baseplate.

At the same end of the baseplate as flange 10a is a further flange 10d which serves to carry a main magnet; the main magnet comprises a core 17 which is butt welded to flange 10d, and upon which is the operating coil 20. The coil is held in position on the core by an internally toothed spring clip 21. The armature for the main magnet includes a rectangular element 22 of soft iron mounted upon a carrier 23 having a substantially vertical flat end 23a and two sides 23b, 23c extending at right angles from it, one along each side of the switch. The main armature 23 pivots on shaft 24 secured to a generally inverted U-shaped saddle 25 fixed to the flange 10c by screws 26. To the ends of the sides 23b and 23c at 27 and 28 is pivoted an inverted U-shaped actuator 30, to which further reference will be made; the base has a depending flange 10f which cooperates with armature of the main magnet.

The movement of actuator 30 in the horizontal direction is limited by arranging the horizontal part of the actuator in a vertical slot or groove 31d in a guide block 31 which lies across the baseplate, between the two rows of finger magnets, and is secured to the baseplate by screws 32. Normally, that is when the main magnet is not energised, the horizontal part of the actuator 30 lies wholly within the slot in the guide block and in particular with its upper edge below the upper surface of the block as shown in Figure 4. When the main magnet is energised, the upper edge of the actuator rises above this surface.

Above the parts of the switch thus so far described is a contact assembly. So far as the construction, support and actuation of the contacts is concerned, this assembly

is generally as described in United States Patent No. 2,630,500, to which further attention is directed.

Briefly, however, the assembly includes a mounting block 33 which is secured to the guide block 31 by screws 34, and sets of both stationary and moving contacts carried on this mounting block. The stationary contacts 35 are clamped in a stack of insulating spacers 36 and the moving contacts 37 are carried but not necessarily clamped in this stack. The stack is clamped to the mounting block by screws 38.

The moving contacts of each set are operated by a card 40; as shown there are seven sets of contacts each with its card. The moving contacts of each set enter slots in the edges of the card, and the cards are guided at their upper ends by means of a tongued spring plate 41, which provides a light downward bias pressure on the cards, and at their lower ends by a relatively rigid plate 42 secured to block 33 by screws 43.

The contact assembly forms a separate unit which can be attached to or removed from the rest of the switch, by means of the screws 34.

When the contact assembly is secured in position, all the cards 40 lie over the upper surface of guide block 31 in the relative lateral position shown in Figure 4. The lower edges of the cards are straight, as shown in Figure 4, and lie parallel to the upper surface of the guide block 31, but in the lowermost position of the cards, corresponding to the non-actuated condition of the contacts, the actuator 30 does not engage the lower edge of the cards of six of the contact sets, even when the main magnet is energised. The exception is the seventh set, which is that shown uppermost in Figure 2. The contacts of this set are the off-normal contacts; they have no finger magnet pertaining to them and they are actuated directly by the actuator 30 upon every energisation of the main magnet. These contacts are required in the circuit of a cross-bar system but hereinafter any reference to the contacts of the relay is to be taken as excluding these off-normal contacts.

So that one vertical set of contacts, pertaining to one finger magnet, can be operated by movement of its card, each finger magnet 11 has an armature which includes an armature element 44 and a spring arm 45, the latter carrying an interference piece 46, while the armatures of finger magnets 14 have correspondingly an element 47 and spring arm 48, the latter carrying an interference piece 50. Normally, that is with a finger magnet not energised, the interference pieces lie to one side of the actuator 30, as shown in Figure 2, the interference pieces 46 lying to the right and the interference pieces 50 to the left of the actuator. When any finger magnet is energised the corresponding armature moves, and the interference piece is brought into position immediately beneath the card 40 and over actuator 30, so that when the main magnet is energised the actuator raises the card and the contact set corresponding to the energised finger magnet is actuated.

It will be seen that the movement of the interference pieces is limited in the actuating direction, that is, in the vertical direction in Figures 1 and 3; each interference piece is limited in its upward movement by the lower edge of the card 40, and in its downward movement by the surface of the guide block 31 upon which it normally rests.

Additionally, and as shown more clearly in Figure 8, the upper surface of the guide block 31 is provided with a series of recesses or grooves 31a, one for each of the interference pieces 46, and corresponding recesses or grooves 31b for interference pieces 50. The lower part of the interference pieces is located, at all times, between the side walls of these recesses and so the interference pieces are likewise limited against movement in the direction at right angles to the interfering and, in this case also, the actuating direction. Since the recesses 31a and 31b have closed ends, the movement of the interference pieces in the interfering direction is also limited. The guide blocks 31 are

also formed with webs 31c which lie between the adjacent armatures.

The armature elements of the finger magnet armatures are arranged to provide the necessary pivotal mounting for the armatures. The elements 44 or 47 are identical in construction through transposed in position in assembly and consist of a rectangular strip of soft iron of which one end is machined to a knife edge as shown at 44a and 37a in Figures 4, 5 and 6. To receive these knife edges, the baseplate is formed with two series of depressions 10e, 10f, the depressions 10e for knife edges 44a and 10f for 47a. As will be appreciated from Figure 2, the depressions 10e are in line, and 10f are likewise in line, and the two lines are parallel with each other. If desired, each row of depressions can be formed as a single elongated depression, but the separate depressions are preferred. It is convenient to form the depressions by a pressing operation, in which case a hole may be formed in the metal before the pressing operation in order that the metal may flow more easily.

The second parts of the armatures are the spring arms 45 and 48. These are also similar in shape, and are formed as stampings of spring material, such as Phosphor bronze or brass. As shown in Figures 5 and 6, spring 25 45 has a flat portion 45a which lies against that face of the armature element 44 which is adjacent the core of the finger magnet, and a flange 45b along each edge to increase the stiffness of the spring. The spring is secured to its element by three small rivets 51. From the 30 bottom edge of the flat portion 45a of the spring extend two small fingers 45c at right angles. These fingers, as will be seen from Figure 4, pass beneath the block 31, the centre part of which is cut away to receive the springs, and engage its under surface; thereby these spring fingers 35 retain the armature elements in position in their respective depressions and they provide also the necessary restoring springs for the armatures.

The spring arms are also formed with bent-over extensions 45d or 48d which serve to carry at their extremities the interference pieces 46 or 50. A method found advantageous for attaching the interference pieces to those extensions is to make each interference piece as shown in Figure 7 as a short cylinder with a flange at one end and an intermediate narrow circumferential groove 46a. The end of each extension has a hole in it, with a slot leading from the hole to the end of the extension. The groove in the interference piece allows the latter to enter the slot and hence the hole, and the interference piece is then deformed endwise to cause it to be firmly and permanently clamped on the extension, and at the same time dimensioned within a close tolerance in the actuating direction.

In the co-pending application No. 451,375 further reference is made to the advantages which are obtained from the construction of finger magnet armature described above, but for the purpose of the present invention it has also the advantage that each armature member 45 or 48 supports the associated interference piece 46 or 50 with sufficient flexibility to allow it to be moved easily in the actuating direction, and also the interference piece to rest with light pressure on top of the guide block 31 in the energised condition of the finger magnet. This latter is an advantage because, as explained above, the contact assembly can be removed as a unit; this assembly includes the cards 40. When the contact assembly is removed in this way the interference pieces will continue to rest in position upon the guide block, and replacement of the assembly is facilitated.

In operation, the interference pieces are moved in two directions, the interfering direction and the actuating direction, as defined above. With the construction described the interfering direction is from left to right or right to left as seen in the view of Figure 4, while the actuating direction is up and down in this figure; clearly

the interference piece must be capable of motion in these two directions. However, this freedom of movement is not in itself sufficient and it must be arranged that no damage will result if the main magnet is operated first, or if its operation is followed instead of preceded by the operation of the finger, and there must be no danger of incorrect operation of the switch in these circumstances.

The mounting of the interference piece on the resilient part of the finger magnet armature, thereby to permit the necessary movement in at least the actuating direction, is advantageous in this respect, but the danger would then normally arise that the interference piece if it moves excessively by the resilience of its carrier may foul some part of the switch and might not be drawn by the finger magnet into the correct position, and incorrect actuation would result.

The construction of switch described avoids this difficulty, since the interference piece, within the limits of its motion in the interfering direction, is limited in its motion in the actuating direction. This will be clear from Figure 4; the lower edge of the card 40 and the upper surface of the block 31 parallel to it define a space within which the card is constrained to move.

In addition, the side walls of the recesses 31a and 31b in the top surface of the guide block 31 are engaged by the interference pieces at all times, so that each interference piece is limited in its movement not only in the actuating direction when it is moving in the interfering direction, but also in the direction at right angles to the actuating direction. Regarded in another way, the finger magnet armature moves its associated interference piece in the interfering direction, but in this movement, notwithstanding the flexibility of its support the interference piece is wholly guided, and it cannot escape from a prescribed path extending between the interfering and non-interfering positions.

Finally, the closed ends of the recesses 31a and 31b limit movement of the interference pieces in the interfering direction, as mentioned above.

By limiting the possible movement of the interference pieces by these various means the danger of misplacement of an interference piece is virtually eliminated and with it the possibility of incorrect operation due to this cause. This is an important practical advantage.

It is not necessary to adjust the extensions 45d, 48d carrying the interference pieces against the surface of the block 31 so that a critical contact pressure is obtained and this is also an important point in manufacture. It will be appreciated that as the actuator lies wholly below the surface of the block when the main magnet is not energised there is no obstruction to the movement of the interference piece, nor any danger of its failing to be inserted in proper position beneath the card. As a result a high degree of reliability is obtained. It is also to be observed that when the contact assembly is secured to the base plate the only operating spacing is that between the card and the surface block. This can be easily achieved in practice, and in any case the tolerance on this spacing is not excessive.

Thus the invention provides a construction of switch which is relatively cheap to manufacture, and of reliable operation.

I claim:

1. An electromagnetic switch device comprising a main operating magnet, a contact set, an operator for the contacts of the contact set, a finger magnet having an armature carrying an interference piece arranged to be moved in an interfering direction upon operation of said finger magnet so as to be interposed between said operator and an actuator arranged to be moved in an actuating direction by the armature of said main magnet, and guide means providing guide surfaces effective over the

range of movement of said interference piece in the interfering direction to limit movement of said piece in directions at a substantial angle to the interfering direction without impeding movement of said piece in the interfering direction.

5 2. An electromagnetic switch device as defined in claim 1 wherein said operator has a substantially straight edge arranged substantially parallel to a guide surface provided by said guide means to define a guide space in which said interference piece is constrained to move.

10 3. An electromagnetic switch device as defined in claim 1 wherein said guide means includes a member providing a guide surface extending over the range of movement of said interference piece, said member being provided with a recess therein to receive said interference piece.

15 4. An electromagnetic switch device as defined in claim 1 wherein said guide means includes a member providing a guide surface extending over the range of movement of said interference piece, said member being provided with an elongated aperture therein providing an interruption in said guide surface, said actuator being arranged to be moved through said aperture upon operation of said main magnet.

20 5. An electromagnetic switch device as defined in claim 4 wherein said member is provided with a recess therein to receive said interference piece, said recess extending across said elongated aperture at a substantial angle thereto.

25 6. An electromagnetic switch device as defined in claim 5 wherein said recess includes a terminal surface serving to limit movement of said interference piece in the interfering direction beyond the position in which it is interposed between said actuator and said operator.

30 7. An electromagnetic relay comprising a plurality of contact sets, an operator for the contacts of each of said contact sets, said operators being arranged in a row, a guide block below said row of operators, said guide block having a plurality of transverse, parallel spaced guide grooves located respectively in alignment with said operators and a second vertical groove extending at a right angle to said guide grooves and intersecting the same, said second groove extending in the direction of said row of operators, a main operating magnet, an actuator member disposed in said second groove of said guide block

35 45 and movable upwardly upon energization of said main operating magnet, a plurality of finger magnets corresponding respectively to said plurality of contact sets, each of said finger magnets having an armature member actuated thereby and an interference piece carried by each

50 50 armature, said interference pieces being received respectively by and slidably guided in said transverse guide grooves from a position to one side of said second groove and actuator when the corresponding finger magnet is unenergized to a position between said actuator and the

55 55 corresponding operator when said finger magnet is energized whereby upon energization of said main operating magnet said actuator will be moved upwardly to engage and effect upward movement of those of said interference pieces which have been brought into alignment with

60 60 said actuator thereby effecting also upward movement of the corresponding operators to engage and actuate the corresponding contact sets.

65 8. An electromagnetic relay as defined in claim 1 wherein the transverse grooves in said guide block are closed at the end in the direction of movement of said interference pieces upon energization of said finger magnets.
